Primary Examiner — George D. Kirschbaum*(74) Attorney, Agent, or Firm* — Margaret Polson; Polson Intellectual Property Law, PC(57) **CLAIM**

The ornamental design for a scooter, as shown and described.

DESCRIPTION

1.-2. Scooters

1.1 : Front

1.2 : Back

1.3 : Left

1.4 : Right

1.5 : Top

1.6 : Bottom

1.7 : Perspective

2.1 : Front

2.2 : Back

2.3 : Left

2.4 : Right

2.5 : Top

2.6 : Bottom

2.7 : Perspective

2.8 : Perspective of folding state

2.9 : Perspective of folding state

1 Claim, 16 Drawing Sheets(56)
